Inventor:
HARRY I. KLAWANS

By
Benjamin, Rooshouse & Lundy Attn:

UNITED STATES PATENT OFFICE.

HARRY I. KLAWANS, OF CHICAGO, ILLINOIS.

MOP MATERIAL.

Application filed April 13, 1922. Serial No. 552,251.

To all whom it may concern:

Be it known that I, HARRY I. KLAWANS, a citizen of the United States, residing at Chicago, in the county of Cook and State of Illinois, have invented a new and useful Improvement in Mop Materials, of which the following is a specification.

My present invention relates to improvements in mops, and has special relation to 10 wet mops employed for washing and wiping up floors and the like with water as contradistinguished from dust mops and the like which are employed for taking up dry dust and are usually impregnated with some dust 15 catching substance of an oily nature. Wet mops are employed in distributing over and rubbing the floor, or other surface to be cleaned, with water in which is usually dissolved an emollient for loosening and dis- 20 solving the dirt. The mop is then rung out and again rubbed over the surface in order to soak up and absorb the cleaning materials and dirt which have been dissolved and loosened thereby. It will at once be per- 25 ceived that mops must be of wear resisting materials so as to stand the hard service to which they are put, and should also be of as absorbent nature as possible so that they may hold a maximum quantity of the clean- 30 ing fluid. Mops have heretofore been made of twisted strands of coarse yarn, or cord, or a woven material made of coarse yarn, twine or cord.

In the manufacture of articles from 35 fibers or filaments of a vegetable or animal origin, such, for instance, as cotton or flax or wool, the fibers or filaments are first disposed in parallel relation by a combing or carding process. Suitable size loosely twisted 40 bundles of the carded material, called slubs or roves, are then taken to the spinning machine and drawn out and spun into yarn for the purpose of giving it the necessary longitudinal strength and reducing it 45 to the desired size for which it is intended. The yarn is then used for knitting or weaving, or two or more strands thereof are twisted together to form thread or twine or string.

It will be seen that the drawing out and spinning of the slubs or roves into yarn, while it adds longitudinal strength to the 50 yarn, also compacts the fibers together and renders the mass much less absorbent, and when the yarn is woven into fabric or

twisted into thread or twine or string it is further compacted and rendered still less absorbent. Slubs or roves have not heretofore been considered suitable mop material as they are so loosely twisted as to be readily 60 pulled out and the severe service which they would receive when formed into mops would quickly destroy them although they are much more absorbent than the spun yarn or any other material made therefrom. 65

My present invention consists of making a mop or strands formed by twisting together a plurality of slubs or roves of fibrous material with a reinforcement which will give the necessary longitudinal strength and 70 wearing quality, thereby securing a mop which will stand the service and will be of greatly increased absorbent qualities and which may be manufactured and sold at a moderate price. I have illustrated a form 75 of mop material embodying my invention in the accompanying drawings which I have found to have both excellent absorbent and wearing qualities, although it will be obvious that a reinforcement of more or less 80 strands or yarns may be employed without departing from the principle of my invention.

In the drawings:

Fig. 1 is a view of a mop embodying my 85 invention, and

Fig. 2 is a view on an enlarged scale of a short length of material from which the mop is made.

Similar reference characters refer to similar elements in the respective views. 90

In the making of my mop I take a suitable number of slubs or roves 3 of suitable material, usually cotton. In Fig. 2 of the drawings, I have illustrated six of these 95 elements, which is a suitable number for mops for ordinary floor use, but it is obvious that a greater or less number may be taken according to the size of the mop which is desired and the use to which 100 it is to be put. With the slubs or roves 3 I also take a string or twine 4 formed in the usual manner by twisting together yarns 5. I have shown in Fig. 2 a string or twine consisting of four yarns. The slubs or roves 3 and the string or twine 4 are then twisted together in the usual manner, but so that the string or twine will lie substantially upon the surface and extend spirally 105 of the slubs or roves. When longitudinal 110

strain is put upon the combined slubs or roves and their reinforcement it causes the reinforcement to straighten and constrict the slubs or roves and absorb the strain which would otherwise pull them to pieces, but when the strain is relieved the parts resume their normal condition. This disposition of the string or twine by gripping the bundle tighter as strain is put on it holds the comparatively loose fibers of the slubs or roves from undue longitudinal extension and therefore from pulling out, while it does not, to any extent, compress or compact them and render them less absorbent. A sufficient number of elements formed as described to make a mop 6 of the desired size are taken and arranged in parallel relation, and I then stitch around and through them at their middle portions a tape 7. When a mop made as herein illustrated and described is subjected to severe service there will be at first some shredding from the ends of the slubs or roves, but when it has been worn so that from a quarter to half an inch of the ends of the twine extend beyond the ends of the slubs or roves it will be found that the mop is then much more wear resisting than the ordinary mops to be obtained on the market, besides being very much more absorbent.

What I claim is:—

1. A mop comprising a plurality of strands, each strand consisting of a twisted bundle of roves of fibrous material with a cord of spun and twisted yarn disposed substantially upon the surface of and spirally of the roves. 35
2. A mop comprising strands composed of roves of loosely twisted absorbent material, and a reinforcement composed of tightly spun and twisted yarn of more compacted and less absorbent qualities; the reinforcement being disposed substantially upon the surface of and spirally of the strands. 40
3. A mop comprising strands each formed of loosely twisted extensible roves of fibrous material, and a comparatively non-extensible reinforcement disposed spirally of said roves whereby longitudinal strain upon said structure will straighten out and constrict said reinforcement around said roves and relieve the latter of the strain. 45 50

Signed at Chicago, county of Cook and State of Illinois, this 4th day of April, 1922.

HARRY I. KLAWANS.
